D. F. JONES

ELECTRIC SWITCH

Filed June 14, 1926

UNITED STATES PATENT OFFICE.

DON F. JONES, OF BELOIT, WISCONSIN.

ELECTRIC SWITCH.

Application filed June 14, 1926. Serial No. 115,711.

My invention pertains more particularly to that type of electric switches known as "start" and "stop" push button switches which are used in the control of an electrically actuated device such as an electric motor.

This type of switch has commonly been used as a means whereby an electric motor could be started or stopped from any one of a number of points remote from the motor. It 10 has been customary in this art to provide two separate actuating buttons for the switch; one to start, and the other to stop the motor. I have found that this method involves an unnecessary multiplicity of parts, and it is, 15 therefore, an object of my invention to provide a control switch of this type in which one button is used to control both the start and the stop circuits.

Another object of my invention is to provide a control switch of the type described in which the operating button may be locked to hold the switch in a neutral or open position.

A more general object is to provide a new and improved switch which is simple and inexpensive in construction, which is efficient and certain in operation, and which has a high factor of safety due to the impossibility of accidental actuation of the switch.

Other objects and advantages will become 30 apparent from the following specification and the accompanying drawings, in which

Figure 1 is a fragmentary sectional view of the switch mechanism taken along line 1 of Fig. 4.

Fig. 2 is a sectional view taken along line 2—2 of Fig. 1.

Fig. 3 is a fragmentary sectional view similar to Fig. 1 showing the contacts in different positions.

Fig. 4 is a fragmentary front elevation of the switch without the case cover.

Fig. 5 is a fragmentary front elevation showing the means for holding the contacts in a neutral or open position.

Fig. 6 is a fragmentary sectional view showing a modified form of a locking member.

Fig. 7 is a fragmentary front view showing the modified lock of Fig. 6.

While I will herein disclose the preferred embodiment of my invention in considerable particularity, for the sake of clearness, I recognize that various alternatives will occur to persons skilled in this art and I therefore do 55 not confine my invention to the present disclosure but aim to cover in the appended

claims all modifications and equivalents falling within the scope of the invention.

My device comprises a pair of contact members mounted relatively to an operating member and movable thereby so that actuation of the operating member axially in one direction will move one of said contact members to close a circuit, and actuation of said operating member in the opposite direction will move the other of said contact members to break a circuit.

The preferred form of my invention, as shown in the drawings, comprises a suitably shaped or moulded base 10 of any good insulating material, adapted to be secured in a protecting casing 11 as by means of bolts 12.

The switch members are secured upon the base, and as shown comprise three substantially Z-shaped terminals 13, 14 and 15, preferably formed of a very good conductor of electricity, such as heavy sheet copper. To these terminals the various circuit leads are secured by means of screws or binding posts 16. Each of the three terminals is secured 80 upon the base through one of the arms of the Z, thus positioning the other arm in parallel spaced relation to the base.

As shown in Figs. 1, 2 and 3, I have formed the terminal 14 with its midsection longer than that of the terminal 15. The two terminals 14 and 15 are so positioned on one end of the base 10 that the outer arm 17 of the terminal 14 will overlie and be parallel to the outer arm 18 of the terminal 15. The third terminal 13 is secured on the opposite end of the base 10 so that the outer arm 19 of that terminal lies in substantial alinement with the overlying arms on the terminals 14 and 15.

Mounted upon the arm 19 of the terminal 13, as shown in Figs. 1 and 3, are two contact members which preferably are in the form of bars 20 and 21 adapted to coact selectively with the spaced arms 17 and 18 to control the circuit. The contact bars may be mounted on the arm 19 in any suitable manner which will permit lateral movement to and from the base 10 but I prefer to mount them so that a resilient means may be readily incorporated therewith. As shown, a single stud, which may be in the form of a bolt 22 passes through the arm 19 of the terminal 13 and also through one end of each of the contact bars 20 and 21 which are positioned on opposite sides of the arm. Encircling the bolt 22 are two helical springs 23 and 24, one being positioned between the head 25 of the bolt 22 and

the contact bar 21 and the other bearing upon the nut 26 on the bolt 22 and the contact bar 20.

By so mounting the two contact bars on the terminal 19 I have provided a simple and effective contact therebetween, and at the same time have incorporated therein the springs 23 and 24 through the agency of which the contact bars will be caused to return to a normal position as will be hereinafter described.

The free ends of the contact bars are offset in opposite directions to such extent that when they are held in a normal position by the two springs the outer contact bar 20 will engage the terminal arm 17 while the inner contact bar 21 will be spaced away from the terminal arm 18. In this manner, I have provided what may be termed a normally closed circuit through the terminal 13, contact bar 20 and the terminal 14, and a normally open circuit through the terminal 13, the contact bar 21 and the terminal 18, any force acting to change the normal position of these contacts being resisted by the springs 23 and 24. When the switch is assembled in a control circuit the normally open contacts comprise the starting switch and the normally closed contacts comprise the stopping switch.

The preferred means by which I actuate the contact arms comprises a cylindrical plunger 27 adapted to reciprocate in a hole 28 through the base 10. A pin 29 to one end of which the plunger 27 is rigidly attached, is freely slideable through appropriate openings in the contact bars 20 and 21, and has secured on its outer end an insulated operating handle 30. The length of the pin 29 is such that when the contact bars 20 and 21 are in normal position the lower bar 21 will be adjacent the plunger 27 and the upper bar 20 will be adjacent the handle 30.

It will be seen that by pushing in upon the operating handle 30 the contact bar 20 will be moved away from the terminal arm 17 thereby breaking the normally closed circuit. If the handle 30 is pulled out, the contact bar 20 is not disturbed, and the contact bar 21 is moved by the plunger 27 to establish contact with the terminal arm 18.

In order to protect the handle 30, I prefer to provide the case 11 with a cover 31 including a central opening 32 through which the handle 30 projects. The cover is formed with an outstanding peripheral flange 33 which serves as a guard against injury or accidental operation of the switch.

I have provided a simple and effective means for locking the switch in a neutral position, that is, a position in which the normally closed circuit is held open and the normally open circuit is held against closing. This means, as shown in Figs. 1, 3 and 5, comprises a pin 34 rigid with the handle 30 and adapted to pass through a slot 35 formed

with the central opening 32 in the cover. To lock the switch, the handle 30 is depressed until the pin 34 has passed through the slot 35, and the handle is then rotated to remove the pin 34 out of registration with the slot 35, so that the pin is held against the inner side of the cover 31 by the spring 23. The contact bars 20 and 21 will then be held in the position shown in full lines in Fig. 3. A modified form of lock is shown in Figs. 6 and 7. In this form, the lock comprises a plate 36 pivotally secured at one end, as at 37, to the cover 31, and having a finger-piece 38 struck up from the other end. A pin and arcuate slot connection 39 between the cover and the plate 36 allows only limited pivotal movement to the plate. One side of the plate is cut away to provide a semi-circular recess which is adapted to fit into an annular groove 40 on the handle 30, and in this manner to lock the handle and contact bars 20 and 21 in the position shown in Fig. 6.

It will be seen from the foregoing description that a switch has been provided which is inherently safe. It will be practically impossible for the switch to be accidentally actuated under any circumstances since it requires a positive and deliberate pull upon the handle 30 in order to operate the switch. Moreover the switch is relatively sensitive when it is desired to break the circuit therethrough, as it is only necessary to depress the handle a short distance in order to move the contact bar 20 out of engagement of the terminal arm 17. The locking means and the flanged cover are other features which lend increased safety to the switch.

The type of circuit in which my switch is adapted to be installed as a remote control or "push button" station is well known in the art, and it is therefore deemed unnecessary to explain in detail the operation of such a circuit. When installed in such a circuit, the normally open circuit formed by the terminals 13 and 15 and the contact bar 21 serves to control the means by which a motor may be started in the following manner. The handle 30 is pulled outwardly, moving the plunger 27 against the contact bar 21 to force the bar against the terminal arm 18 as shown in broken lines in Fig. 3, thereby closing the normally open circuit. This energizes an electromagnetic switch, which in closing will close an auxiliary switch, thereby completing a maintaining circuit through the normally closed circuit formed by the terminals 13 and 14 and the contact bar 20. The handle 30 may then be released, and the electromagnetic switch will remain closed. To stop the motor, the electromagnetic switch is deenergized by depressing the handle 30 to force the contact bar 20 away from the terminal arm 17 as shown in full lines Fig. 3, thereby breaking the normally closed circuit.

I claim as my invention:

1. An electric switch comprising, in combination, a base, three circuit terminals mounted on said base, each of said terminals having a contact surface in spaced relation 55
 5 from and substantially parallel to said base, two of said terminals being mounted on said base so that their contact surfaces are positioned one ahead of the other, a pair of contact members movably mounted on said third 60
 10 terminal and extending therefrom in the same general direction, a spring cooperating with each of said contact members for holding said members in a predetermined position with respect to said terminal, said contact surfaces 65
 15 of each of said two first mentioned terminals being arranged to be selectively engaged by said contact members. 70
2. An electric switch comprising, in combination, a base, three circuit terminals 75
 20 mounted on said base, two contact bars mounted on one of said terminals, resilient means cooperating with said contact bars to hold said bars yieldingly in engagement with said terminal, one of said bars being adapted 80
 25 to contact with one of the remaining terminals to form a normally closed circuit and the other of said bars being positioned adjacent to but out of contact with the other remaining terminal to provide a normally open circuit, a 85
 30 single means for actuating said bars against the action of said resilient means, and locking means whereby both said normally open circuit and said normally closed circuit may be held open. 90
3. An electric switch having, in combination, a base, three terminals on said base, a contact bar movably mounted on one of said terminals and having contact with one of the remaining terminals to provide a normally 95
 40 closed circuit, a second contact bar also movably mounted on said first mentioned terminal and arranged to be moved into contact with the third terminal, thereby providing a normally open circuit, and a single operating 100
 45 means engaging both of said contact bars for opening said normally closed circuit and for closing said normally opened circuit. 50
4. An electric switch having, in combination, a base, three terminals on said base, a contact bar movably mounted on one of said terminals and having contact with one of the remaining terminals to provide a normally closed circuit, a second contact bar also mov- 55
- ably mounted on said first mentioned terminal and arranged to be moved into contact with the third terminal thereby providing a normally open circuit, means for actuating said bars, and locking means cooperating with said actuating means to hold both of said normal circuits in an open position. 60
5. An electric switch having, in combination, a base, three terminals mounted on said base, two of said terminals being so formed and arranged that a portion of one is positioned apart from and parallel to a similar portion of the other, two contact bars pivotally mounted on the third of said terminals, and two springs, one cooperating with each of said contact bars to hold said bars in a normal position relative to the two first mentioned terminals. 65
6. An electric switch comprising, in combination, a circuit terminal, two relatively movable contact bars mounted thereon, two springs, one cooperating with each of said contact bars to hold said bars in engagement with said terminal in predetermined normal positions, a single operating means for imparting movement to said contact bars, a circuit terminal adapted to be engaged by one of said contact bars, and a second circuit terminal adapted to be engaged by the other of said contact bars, said last mentioned terminals being arranged so that the portions which are engaged by the contact bars are positioned in parallel spaced relation. 70
7. An electric switch comprising, in combination, a base, a plurality of terminals mounted on said base, a plurality of movable contact members mounted on one of said terminals adapted to selectively engage the others of said terminals, yielding means tending to hold one of said contact members normally in engagement with another of said terminals and tending to hold another of said contact members normally out of engagement with another of said terminals and a single actuating means for said contact members, said means upon movement in one direction tending to separate said normally closed parts and upon movement in the other direction tending to bring into engagement said normally separated parts. 75
- In testimony whereof, I have hereunto affixed my signature.

DON F. JONES.
